(57) **CLAIM**

The ornamental design for reversible heart-shaped mold, as shown and described.

DESCRIPTION

FIG. 1 is a top perspective view of the reversible heart-shaped mold;

FIG. 2 is a bottom perspective view of the reversible heart-shaped mold shown in FIG. 1;

FIG. 3 is a bottom plan view of the reversible heart-shaped mold shown in FIG. 1;

FIG. 4 is a cross-sectional view of the reversible heart-shaped mold in FIG. 3 along the A-A axis; and,

FIG. 5 is a top plan view of the reversible heart-shaped mold shown in FIG. 1.
